ARTHUR PRICE, OF AUBURNDALE, MASSACHUSETTS.

FIRELESS FURNACE.

1,235,840.

Specification of Letters Patent.

Patented Aug. 7, 1917.

Application filed January 23, 1917. Serial No. 144,296.

To all whom it may concern:

Be it known that I, ARTHUR PRICE, a subject of the King of Great Britain, residing at Auburndale, in the county of Middlesex 5 and State of Massachusetts, have invented a new and useful Improvement in Fireless Furnaces, of which the following is a specification.

My invention relates in a general way to 10 the methods of generating steam; and particularly to the use of inflammable gases for such purposes, with special reference to the conservation of heat by means of radiators initially heated by said gas, and such heat 15 greatly conserved and more fully utilized than by any previously known devices.

My objects are; first, to replace the use of 20 coal by the use of an inflammable gas; second, to provide a series of radiators so constructed as to be adapted to be heated by a properly formed gas torch; third, to provide a gas torch suitable for the purposes of 25 heating these radiators; fourth, to surround the radiators by a double casing, one within the other, the space between the two to be 30 filled with mineral wool or other similar material which is a nonconductor of heat; fifth, to close all the flues of the boiler permanently except a single row farthermost from the front, and to arrange these with covers 35 that may be opened during the period of initial heating.

I accomplish the results sought by means 40 of the mechanism illustrated in the accompanying drawings, in which—

Figure 1 is a front elevation of a rectangular boiler fitted with my device, which is shown partly in section.

Fig. 2 is a side elevation, partly in section. 45 Fig. 3 is a plan view, partly in section.

Fig. 4 is an isometric view of one of the radiators; and

Fig. 5 is an isometric view of the gas torch for use with said radiators.

Similar reference letters refer to similar parts in the several views.

In the drawings A, is a cast iron boiler of the usual construction, having vertical flues or spaces *a*, for the escape of the products of 50 combustion when coal is used for fuel.

The ordinary coal burning firebox has been removed and my device substituted therefor. This device consists of a double box-like form, the inner box B, surrounded 55 by the outer box C, inclosing the rear, both

sides and the bottom, the space between them being closely packed with mineral wool or similar substance D, which is a non-conductor of heat. The inner box B, is divided into any number of compartments, (in this case four,) by the longitudinal partitions *b*, *b*, *b*, forming separate spaces for the radiators E, E. In each of these compartments is placed a platform F, supported upon four or more short levers *f*, *f*, fixed to the shafts G, G, and operated by the hand levers *g*, *g*, outside of the outer box C, and by means of which the platforms may be raised or lowered. Pivoted in the vertical sides of the platform F, is a series of friction rollers H, H, adapted to facilitate the introduction and withdrawal of the radiators E, E.

Resting upon the friction rollers H, are the radiators E, E, each consisting of a rectangular mass of metal, (preferably cast iron), having near the base a cylindrical hole *e*, for the introduction of the gas torch J, and the space beneath said hole cut away as shown. Radiating from the cylindrical hole *e*, are numerous lines of holes terminating at the top and sides.

The gas torch J, is a metallic pipe covered with cement composed of non-conducting material and fitted with a multiplicity of jets arranged in longitudinal lines substantially coinciding with the line of holes in the radiators E, E. The gas torch J, is connected by a flexible tube with any convenient source of gas supply.

Referring to Fig. 3, it will be seen that each compartment is closed by two doors, an inner door K, and an outer door L, each hinged and very tightly fitting. The inner door is connected by a horizontal rod *k*, with the right angle lever M, (Fig. 2) from which the vertical rod *m*, connects with the door N, closing the top of the flue or air space beneath it.

The operation of my device is as follows; The doors K, and L, being open, (and the vent door N, also open,) the radiators E, E, are put in place, resting upon the rollers H, H, the platform F, being at its lower position, as shown in Fig. 2. The gas torch J, is introduced into the radiator and ignited, the products of combustion passing up through the rear flues *a*, and out past the door N. This action is continued until the radiator is as hot as desired. The gas torch is withdrawn, the inner and outer doors 100 105 110

tightly closed and by means of the levers *g, g*, the radiator is raised to a position as close to the under side of the boiler as may be. This process is repeated with each radiator in turn until all are heated and the generation of steam proceeds.

Of course it is to be understood that I do not confine myself to a rectangular boiler, as my device can be adapted to a cylindrical boiler whether horizontal or upright, or to various forms of cast iron boilers, means being adopted to close all exits for air and gases except a few at the rear end, and these being provided with automatically closing devices.

It is also to be understood that as my object is to conserve and prevent the loss of heat, other methods, such as producing a vacuum in the space between the inner and outer walls of my heating space may be adopted. However I have shown what I consider the preferable method.

Having described the construction and operation of my device, I claim:—

1. In a device of the character described, the combination of radiators, platforms provided with rollers supporting said radiators, a steam boiler adapted to be heated by said radiators, and means for lowering said radiators to a position for heating and raising them into near contact with said boiler to be heated.

2. In a steam generating device, the combination of a steam boiler, a heat generating furnace consisting of a plurality of compartments adapted to contain heat radiators, platforms provided with rollers and adapted to support said radiators, doors adapted to close the front of said compartments and also the gas exits of said boiler, substantially in the manner and for the purposes set forth.

ARTHUR PRICE.
